UNITED STATES PATENT OFFICE.

ARTHUR SWEET, OF SALT LAKE CITY, UTAH.

CONFECTION PACKAGE.

Application filed August 25, 1925. Serial No. 52,433.

My present invention relates generally to confection packages and more particularly to a candy sales and display container adapted for use in the sale of confections of this general nature to retailers as well as its subsequent employment in part at least in the sale to consumers.

Among its many objects my invention aims to provide a confection package so constructed and arranged as to form a strong compact box for the sale of confections to retailers including a display tray and provide for the ready, quick removal of certain elements whereby to expose the confection contents without necessitating unpacking or transfer of such contents in the manner required at present.

In the accompanying drawing forming a part of this specification and illustrating my invention,

Figure 1 is a perspective view showing the complete confection package partly broken away and in section, and

Figure 2 is a vertical longitudinal section taken therethrough.

Referring now to those figures, my invention proposes a confection package including a base 10 having a surrounding flange 11 and in practice preferably im- 30 pressed, colored or otherwise ornamented or embellished to form a display tray within the display case or upon the counter of a retail store and the like where it is im- 35 portant that the goods be displayed to the purchasing public.

The flanges 11 of the base section 10 are adapted to receive therein the lower edges of the side and end walls 12 and 13 with a sufficiently loose fit to permit these walls to 40 be readily elevated out of the base section 10 and yet a sufficiently tight fit to reinforce these walls and prevent the same from outward bulging.

The upper edges of the side and end walls 45 are telescoped by a flanged cover or lid 14, the flanges 15 of which also assist in reinforcing the side and end walls while the package is in its original form.

Within the container thus formed, the 50 confection contents shown at 16 are ar-

ranged upon trays 17 superposed upon one another and disposed in the first instance upon a false bottom in the form of a plate 18 resting at its edges upon the inner sloping portion of the tray-like base 10 and additionally supported by a flanged lower supporting piece 19. Thus upon removal of the walls 12 and 13 as well as the cover 14, the vertical series of trays will remain upon the base 10 and the confections fully exposed to the purchasing public, or, if desired, the several trays and the false bottom 18 as well as its support 19 may be removed and the candy suitably and attractively arranged upon the tray-like base 10.

It is obvious that in the manner described my invention avoids the delays and disadvantages necessary at present in unpacking the ordinary confections and transferring the same to display trays or dishes whereby 70 they may be exposed to consumers, and it is equally obvious my invention accomplishes the foregoing in a manner which will readily commend itself to retailers, without otherwise complicating the usual 75 construction and without adding in any material extent to the cost thereof.

I claim:

A confection package including a base section in the form of a display tray having 80 upwardly and outwardly inclined side walls equipped with upturned peripheral flanges, a false bottom supported within and resting on the inclined walls of the base section, a support under said false bottom resting on 85 the bottom of the base section, said false bottom and support being removable from the base section or tray, side and end walls and a cover removable from said base section or tray, and confection holding trays 90 on the base section or tray and arranged in superposed relation to support confections in exposed position thereon when said side walls and cover are removed, the side and end walls being inserted within the flange 95 of the base section between it and the bottom confection holding tray whereby said walls are held against bulging.
